JAMES F. McELROY, DECEASED, ASSIGNOR TO CONSOLIDATED CAR-HEATING COM-
PANY, A CORPORATION OF WEST VIRGINIA.

ELECTRIC SWITCH.

1,160,921.

Specification of Letters Patent. Patented Nov. 16, 1915.

Application filed August 11, 1911. Serial No. 643,576.

To all whom it may concern:

Be it known that I, JAMES F. McELROY, a citizen of the United States, residing at Albany, county of Albany, State of New York, have invented certain new and useful Improvements in Electric Switches, the following being a full, clear, and exact disclosure of the one form of my invention which I at present deem preferable.

For a detailed description of the present form of my invention, reference may be had to the following specification and to the accompanying drawing, which illustrates my invention.

Figure 1 is a top plan view of the switch, the casing being in section; Fig. 2 is a front elevation thereof, the casing being in section, and Fig. 3 is a side elevation thereof with the casing being in section. Figs. 4 and 5 are detail views illustrating a switch handle, and the switch base respectively.

My invention relates to an electric switch of the type in which the switch is normally centralized by a spring and designed to be temporarily operated against the force of the said spring, and it consists in certain details of construction to be hereinafter described, including an arrangement whereby a single spring serves both to centralize the switch arm and lock it in its central position. Moreover, I have constructed my switch with reference to its placement in a partition, the casing being constructed with reference to such location and divided generally speaking into two compartments, one containing the switch proper and the other serving as a junction box, one compartment also being in front of and the other in rear of the partition in which the instrument is placed. The rear compartment, which also serves as a junction box, is provided with a removable cover and with an opening for admitting the line wires to the junction box.

In the accompanying drawing F represents the casing, which is provided, midway of its depth, with flanges f by which it may be secured to a partition E. The front portion of this casing contains the switch arm and contacts, while the rear portion projects through the partition and forms a junction box accessible from the rear and provided with a removable cover F'. The front portion of the casing is open on its lower side to provide for the operation of the switch

arm by the external handle A', while the rear portion forming the junction box also has on its lower edge an opening for the conduit G containing the line wires. This opening is formed for convenience in the cover portion F'.

Inside of the casing and midway of its depth is an insulating base D which forms two compartments therein and also supports on its front side the switch proper. The stationary part of the switch proper is formed by a casting which has a flat base C resting upon and secured to the aforesaid insulating base D, and projecting forward from said base C is a ring-shaped extension C'. The opening in this ring is shown in dotted lines at c, Figs. 1 and 3. The movable portion of the switch consists of the switch-arm casting A having formed integral therewith at its upper end a disk B somewhat larger in diameter than the opening c in the aforesaid ring-shaped extension C'. The disk B extends transversely across the switch arm to form a transverse extension thereof. On the face of the disk B are two perforated lugs b b. Through the lugs b b passes a pin K, one end of which projects outward beyond the lug into a slot formed between the two projections c' c' on the ring-shaped part C'. The opposite end of pin K projects inward beyond the perforated lug b into an opening in the flat base portion C of the stationary casting. This provides a stop against rotation of the switch arm on its longitudinal axis. The aforesaid disk B bears on its under flat face against the upper flat face of the aforesaid projection C' which forms a seat therefor and is held in that position by the spring S which is secured at one end to the disk B, being, for example, bent around the aforesaid pin K, and at its other end is anchored to a stud c' on the base C of the stationary casting. Assuming the casing to be removed the stationary and movable castings will be assembled in the position shown by passing the handle A' of the switch arm A down through the opening c in the ring-shaped projection C', until the disk B is seated upon said projection; then the spring S is attached at one end to the pin K and at its other end to the stud c', as just mentioned. The movable part is there-

fore not definitely pivoted upon the stationary part, but the two parts are drawn together and secured in their working relation by the spring S, and the switch arm 5 A can still be moved to either side of its central position in an arc about one edge of the disk B as a center. The spring S will then exert its eccentric tension on the switch arm, thereby tending to centralize it by bringing the flat face of the disk B into engagement with the upper flat face of the ring-shaped projection C'. The switch arm A is thus movable laterally away from and into its central position, 10 but it also is capable of a similar outward movement away from, or an inward movement toward the base plate C of the stationary casting, while the spring S similarly resists such outward movement of the 15 arm. The purpose of the latter movement is to enable the spring to not only centralize the switch arm with respect to its lateral movements, but also to lock it in its central position by causing a projecting lug A², 20 on the under side of switch arm A near the handle, to fall into a notch a formed for its reception in the aforesaid base plate C of the stationary casting. Thus, referring particularly to Fig. 3, it will be manifest that, if the handle A' is moved outward or to the left to disengage the projection A² from the notch a, the switch arm will tend to rotate about the right hand edge of the disk B as a center and such 25 movement will be resisted by the spring S. Consequently, in order to operate the switch it is necessary to first move the handle A' outward against the force of the spring S, to disengage the lock, and then 30 move it laterally to one side or the other, also against the force of the spring S, to close the contacts on one side or the other. Conversely, when the handle is released the 35 spring S will first act to centralize the switch arm and then when the projection A² comes into line with the notch a, it will furthermore act to force the said projection into the notch and lock the arm in its central position. This construction affords 40 a simple, cheap and rugged switch and one that is also reliable in operation for the special purpose that it is designed to serve. In particular the switch is used on railway 45 cars for the control of door-operating machinery. For that purpose it is placed at the end of a car, in the wall or partition E formed by the end wall of the vehicle, so as to be convenient for the trainman who stands on the outside platform. At the 50 same time the rear portion of the switch-casing projects through the wall or partition E and is conveniently accessible from the rear, for the purpose of receiving the wire-conduit G and connecting the wires 55 to the switch by means of the binding

screws on the back of the insulating base or partition D within the casing.

What I claim as new and desire to secure by Letters Patent is:

1. In an electric switch, a base and a switch arm each provided with complementary members coöperating to lock the switch arm in a central position, and a spring acting to move the arm to said central position and also to maintain an engagement of said complementary members. 70
2. In an electric switch, a switch-arm, a lug and a notch carried by the base and the arm respectively for holding the arm in its central position relative to the base, and a spring 80 acting to both centralize the arm and hold it into locking engagement with the base.
3. In an electric switch, a base, a switch-arm movable in two angular directions relative to the base, and a double-acting spring 85 operating to retain the arm in a central position relative to the base by moving said arm in one direction and to a locked position by moving it in a second direction at an angle to the centralizing movement. 90
4. In an electric switch, a stationary part, a movable part loosely seated thereon having a movement in an arc with respect to the stationary one, and a spring holding the two parts in engagement. 95
5. In an electric switch, a stationary part, a movable part seated thereon and having a movement in an arc with respect to the stationary one, said stationary and said movable parts having complementary locking means, and a spring for holding the two parts in both working and locking engagement with each other. 100
6. In an electric switch, a switch-arm having a transverse bearing plate, a seat for said plate, and a spring tending to hold the plate to its seat. 105
7. In an electric switch, a switch-arm having a transverse bearing disk, a seat for said disk, a spring pressing the disk against its seat, and a stop for preventing axial rotation of the arm. 110
8. In an electric switch, a stationary part provided with a base, and a seat projecting therefrom, a switch-arm having a disk bearing, and a spring acting upon said disk to force it to said seat. 115
9. In an electric switch, a switch arm provided with a transverse extension and a seat therefor and movable in two angular directions on the edges of the said transverse extension as centers, and a spring acting to force the said transverse extension to its seat. 120
10. An electric switch comprising a base having an angularly projecting seat, a switch arm having a bearing disk loose on the seat, said base being provided with a notch and the arm being provided with a lug, and a spring connection between the 125
11. An electric switch comprising a base having an angularly projecting seat, a switch arm having a bearing disk loose on the seat, said base being provided with a notch and the arm being provided with a lug, and a spring connection between the 130

arm and base for holding the disk to the seat and to cause the lug to engage the notch.

11. An electric switch comprising a base provided with a seat, a switch arm having a bearing that loosely engages the seat to permit the arm to have an outward and lateral movement relative to the base, coöperating locking members carried by the base and arm, and a spring connection opposing movement of the arm relative to the base and normally causing an engagement of the locking members of the arm and base.

12. An electric switch comprising a base

having a flat open seat projecting therefrom, a switch arm projecting through the seat and having a bearing disk loose on the seat, coöperating locking members carried by the arm and base, and a spring normally holding the disk to the seat and the locking members engaged.

In witness whereof I have hereunto set my hand, before two subscribing witnesses, this 9th day of August, 1911.

JAMES F. McELROY.
